UNITED STATES PATENT OFFICE.

JOSEF KELLNER, OF BROOKLYN, AND SIDNEY WORMS, OF NEW ROCHELLE, NEW YORK,
ASSIGNORS TO FRANKLIN KNITTING MILLS, OF NEW YORK, N. Y., A CORPORATION
OF NEW YORK.

MUFFLER.

1,072,735.

Specification of Letters Patent.

Patented Sept. 9, 1913.

Application filed March 28, 1913. Serial No. 757,284.

To all whom it may concern:

Be it known that we, JOSEF KELLNER, a subject of the Emperor of Germany, and SIDNEY WORMS, a citizen of the United States, residing, respectively, at Brooklyn, in the county of Kings and State of New York, and New Rochelle, in the county of Westchester and State of New York, have invented certain new and useful Improvements in Mufflers, of which the following is a specification.

The present invention relates to mufflers and more particularly to knitted mufflers, the object thereof being to provide an improved knitted muffler having a neck portion of comparatively short length merging into a pair of flaring or gradually widening ends, both substantially alike.

A further object of the invention is the provision of a knitted muffler knitted of lengthwise extending ribs or wales so that when knitted of different colored threads it will have an accordion effect, the flaring ends of which terminate in shaped ends, each preferably of a single fold or thickness.

In the drawings accompanying and forming part of this specification, Figure 1 is a plan view of this improved knitted muffler, Fig. 2 is a rear view of one end thereof.

Similar characters of reference indicate corresponding parts in the figures of the drawings.

The knitted muffler 1 is given its iridescent or accordion effect lengthwise thereof by knitting the same of different colored threads so as to form lengthwise extending wales or ribs 3 of one color alternating with the intermediate rows 4.

In knitting this improved muffler it is started with a certain width in the machine, such as a flat knitting machine, it being started for instance at the end 5 and by gradually throwing out of operation certain needle loops or stitches, it is so knitted that the end will gradually taper or narrow toward the neck portion the edges of which are knitted in substantial parallelism or with slight curvature thereof. By gradually throwing into operation certain needle stitches or loops the opposite portion 7 is knitted with a similar flaring end. The muffler when knitted flat in the manner described is then formed up so that the rear edges thereof will be brought together as at

8 and sewed or connected along such edges. 55 Each end of the muffler is shaped, shown herein as of triangular shape, as at 9, and overedged, this shaping being usually done prior to the sewing of the rear edges together. This overedging may be done with 60 different colored threads corresponding with the body of the muffler, if desired. The rear connected edges of the muffler are barred by a crosswise extending bar 10, (see Fig. 2) thus providing a loose flowing end at each 65 end portion of the muffler. Thus it will be observed that this improved double flaring end knitted muffler is knitted in the desired shape as contradistinguished from being cut from a knitted blank, and that when of an 70 iridescent or accordion appearance it is preferably knitted with lengthwise extending wales or ribs, and horizontal courses, and preferably with the face of the muffler of contrasting colors, while the rear of the 75 fabric may usually be of a solid or single color so that in some instances the wearer should he be so disposed, could use the muffler with the wrong side out, the ends preferably being open and suitably shaped as 80 shown in the present instance as of triangular shape.

This improved muffler it will be observed has a relatively short neck portion, in other words, the neck portion is stubby or blunt 85 and this neck portion terminates in two similarly formed ends both of which are of the same or substantially the same size so that the ends are interchangeable, that is to say, either end may be folded on top of the 90 other in use. By reason of the short neck portion it will be obvious that the flaring ends will be in such position that they will cover substantially the entire breast or bosom of the wearer.

While the neck portion of this muffler or chest protector is narrow as compared with the width of the shaped ends, yet as a matter of fact the neck portion is of considerable width sufficient when placed around the 100 neck of the wearer to usually cover the collar and such portion of the back of the neck above the collar as it is desired to protect. In short, the neck portion of the muffler is what may be considered of stocky construction, that is short and wide, yet relatively narrow as compared with the ends. In practice the muffler as ordinarily formed

will have its neck portion about five inches wide, while the greatest width of its shaved ends may be approximately ten inches wide.

We claim as our invention:

- 5 As an article of manufacture, a muffler or chest protector knitted flat with a short stocky neck portion sufficiently wide to protect the neck of the wearer above the collar, but relatively narrow as compared with the
- 10 ends of such muffler, said neck portion merging into a pair of substantially similarly formed flaring ends whereby they are interchangeable, each of comparatively great width at its widest portion and of sufficient
- 15 width between its point of juncture with the neck portion and its end to, when overlapping its companion end, protect the chest of

the wearer, each of said ends terminating in a shaped end, said muffler being knitted with substantially the same form of stitches from 20 end to end and having lengthwise extending ribs or wales which may alternately be of different colors on one or both sides thereof to provide an accordion effect, the juxtaposed rear edges of such muffler being united 25 on the rear side thereof.

Signed at New York, this 15th day of March, 1913.

JOSEF KELLNER.
SIDNEY WORMS.
